COMBINED CANISTER AND COVER

Earl S. Tupper, Upton, Mass.

Application February 5, 1953, Serial No. 23,452

Term of patent 14 years

(Cl. D44—1)

To all whom it may concern:

Be it known that I, Earl S. Tupper, a citizen of the United States and resident of Upton, county of Worcester, and State of Massachusetts, have invented a new, original, and ornamental Design for a Combined Canister and Cover, of which the following is a specification, reference being had to the accompanying drawing, forming a part thereof.

In the drawing:

Figure 1 is a perspective view of a combined canister and cover embodying my new design;

Figure 2 is a top plan view thereof;

Figure 3 is a front elevational view thereof partly cut-away and in section;

Figure 4 is a bottom plan view thereof.

I claim:

The ornamental design for a combined canister and cover, as shown.

EARL S. TUPPER.
